UNITED STATES PATENT OFFICE.

GUNNAR MADVIG, OF OAKLAND, CALIFORNIA.

DESIGN FOR A CENTER ORNAMENT FOR DRAPERY POLES AND RODS.

Application filed February 21, 1928 Serial No. 25,518. Term of patent 3½ years.

To all whom it may concern:

Be it known that I, GUNNAR MADVIG, subject of the King of Denmark, and a resident of the city of Oakland, county of Alameda, State of California, have invented a new, original, and ornamental Design for a Center Ornament for Drapery Poles and Rods, of which the following is a specification, reference being had to the accompanying drawings, forming part thereof.

The figure is a face view of the center ornament illustrating my design.

I claim:

The ornamental design for a center ornament for drapery poles and rods substantially as shown.

GUNNAR MADVIG.
